MUSICAL INSTRUMENT

James Manatt, Chicago, Ill., assignor to Central Commercial Company, Chicago, Ill., a corporation of Illinois

Application August 11, 1939, Serial No. 289,541

3 Claims. (Cl. 84—1.19)

This invention relates to electrical musical instruments for simulating organ and orchestral tones.

In my co-pending application Ser. No. 283,554, filed July 10, 1939, I disclose and claim an electrical network, the characteristics of which are such that upon simultaneously playing two or more keys of a single manual and drawing one or more stops, proportionality is secured between 10 current and voltage, the current increasing in ratio to the number of keys played simultaneously without increasing the voltage and whereby the intensity of the output voltage is definitely a function of the current. In consequence of these 15 circuit characteristics, notes played simultaneously add to each other in a manner typical of the pipe organ.

The novelty present in the improvements herein set forth and claimed consists in connecting a 20 system of stops in the aforesaid electrical network and employing same in conjunction with the speaking stops of a plurality of manuals and a pedal section to produce crescendo and diminuendo effects.

25 It is well known that all musical tones are composed of a fundamental tone and a series of "upper partials," the completeness or incompleteness of which and the prominence or weakness of said partials relative to each other and to the fundamental constitute those influences which cause the difference in tone quality between two musical sounds of the same pitch and are therefore the acoustical factors which produce the difference in tone-quality between different notes and different 30 organ stops. In the embodiment of my invention herein disclosed and claimed, stops for crescendo effects are electrically connected in said electrical network and with a synthesizing system, whereby the prominence or weakness of the partials can be 35 correctly determined acoustically and accurately controlled so that organ and orchestral tones can be faithfully simulated and qualities for crescendo effects correctly added to each other to suit any desired registration and without the possibility of 40 interference between the partials composing different qualities.

45 A further feature of the invention resides in the forms and arrangements of stops which are progressively actuatable, one at a time, from softest to the loudest and are controlled from a common foot pedal.

50 A further object is to provide an electrical musical instrument in which signals at different partial frequencies are produced by alternators common to all stops of the instrument.

A still further object is to provide an electrical network having an expression control for the upper manual and the crescendo stops for said manual and a separate expression control for the lower manual, the pedal keyboard and the crescendo stops for said lower manual and said pedal keyboard, the controls adapted to be actuated either singly or together from respective expression pedals and with one foot of the player while the other foot is employed to actuate all of said 10 crescendo stops.

The invention will be more fully understood by reference to the following description when read in connection with the accompanying drawings in which:

15 Figure 1 is a schematic illustration of a portion of the electrical network showing the alternators for producing signals at different partial frequencies.

Figure 2 is a view similar to Figure 1 showing 20 the portion of the network which includes the various organ stops and the crescendo stops of the instrument.

Figure 3 is a schematic view of the amplifying and sound producing systems and

25 Figure 4 is a view in elevation of a mechanical control means for effecting actuation of the crescendo stops.

In carrying the invention into practice, use can be made of any well known system adapted to provide 30 alternating voltages at the tone frequencies of the notes of the musical scale.

While I show an organ having two manuals and a pedal keyboard, I may add to or take from the number of manuals without departing from 35 the spirit and intention of my invention and can classify the various stops to suit any desired registration. In like manner, the crescendo stops may consist of any suitable number depending upon the size and musical range of the instrument. 40

In the accompanying drawings, I show playing keys C¹ and C² of the upper manual; keys C¹ and C² of the lower manual and pedal keys C⁰ and C¹. The letters and their numerical exponents employed herein denote the octave relationship 45 of the notes to each other.

I also show speaking stops 50, 60 and 70, each denoting a particular quality in a set of such stops for each manual and said pedal keys.

50 In addition to the aforesaid speaking stops 50, 60 and 70, I show stops 80, 90 and 100. In practice, there will be a plurality of stops 50 for the upper manual, a plurality of stops 60 for the lower manual and a plurality of stops 70 for the pedal keyboard.

In the accompanying drawings, I show sets of electrostatic alternators respectively distinguished from each other by the letters C, E, G and A#, each said set consisting of eight individual, continuously varying, coaxial condensers respectively numbered 0, 1, 2, 3, 4, 5, 6 and 7. Each individual condenser comprises a rotor 10 and a pair of stators 11 and 12, the stators being capacitatively related to the rotor by a thin air dielectric. All 10 rotors of an assembly are fixed to a rotary shaft 13, and as shown in Figure 1, each shaft is adapted to be polarized through a brush 14 supplied with potential from a direct current source 15.

In practice, twelve alternator assemblies are 15 preferably employed, each assembly designed and adapted to constitute a complete organization for the production of alternating voltages at the tone frequencies of partials in octave relation. The four assemblies shown in Figure 1 will therefore 20 be considered merely a part of the total number of assemblies for a complete musical instrument. Each assembly will be driven at its own speed which will be different from that of the assembly next adjacent thereto by the twelfth root of two. 25 In this manner, alternating voltages at the tone frequencies of the notes of the equally-tempered musical scale will be produced.

The rotor 10 of any individual condenser herein 30 shown can be properly considered a primary electrode and the stators a secondary electrode in which the waveform areas of the secondary electrode are adapted to be periodically scanned by capacity areas on said primary electrode to thereby electrostatically produce alternating voltage 35 of sinusoidal waveform, the frequency of which corresponds to the note of the scale to which said condenser is assigned.

As shown in Figure 1, the oppositely disposed stators 11 and 12 of a condenser are electrically 40 connected or tied together at 16 and connected to an output conductor 17. Connected across each output conductor and to a common ground connection 18 in the network herein employed is an impedance element 19 for controlling the exact 45 amount of voltage necessary to be drawn from a condenser for use in said network.

Upon referring to Figure 2 of the drawings, it 50 is noted that each manual of the instrument is individual to a particular set of bus-bars, i. e., a system of ten bus-bars 20 is provided for the upper manual; a similar system for the lower manual and a similar system for the pedal keyboard. Reading from left to right in said figure, the bus-bars 20 for said upper manual are distinguished 55 from each other by notations indicative of different harmonic series of partial frequencies which the bus-bars serve to conduct. That is to say, the first bus-bar in the series serves as a channel for all frequencies of the sub-fundamental series; the second as a channel for all frequencies of the fundamental series; the third as a channel for all frequencies of the order of the organ 5th; the fourth as a channel for all frequencies of the second partial series; the fifth as a channel for all frequencies of the third partial series and so on, through and inclusive of the last bus-bar which serves as a channel for all frequencies of the 8th partial series. In series 60 with each bus-bar is a low resistance 220, one terminal of which is connected to said common ground. As the three systems of bus-bars are identical in every major respect and similarly connected in said network, it is thought that the 65 description just given of the system for the upper manual will suffice for all of said systems.

In the schematic illustration of the circuits shown in Figure 2, it is noted that the playing keys C1 and C2 of the upper manual are each thereof provided with a set of switches consisting of ten similar contact elements 21, disposed so 5 that the upper contact element of each set will be close circuited with the bus-bar denoting the sub-fundamental frequencies when the keys are depressed. The next contact elements will be close circuited with the bus-bar denoting the fundamental frequencies and so on downwardly in the series of contact elements in each set and throughout the remaining bus-bars, to and inclusive of the bottom contact element and the bus-bar which 10 serves as a channel for all 8th partial frequencies. 15

To this point in the description, it will be entirely clear to persons trained in the art to which the invention relates that upon connecting contact elements of switches of different playing keys of any manual with the continuously varying 20 condensers or alternators in the manner herein shown, contact elements of different keys are common to the same alternator, whereby when depressing a key, alternating voltages at harmonically related frequencies will be simultaneously impressed upon different bus-bars for a composite waveform of output voltage corresponding to the note assigned to said key. Hence, each output conductor has connected thereto as many branch circuits 22 as are required for the 25 production of voltage of the same tone frequency to contact elements of different keys. It follows that any alternator in the system of alternators herein disclosed furnishes alternating voltage of the fundamental frequency of one or more notes assigned to the keys of different manuals, the same frequency serving as harmonics of others of said notes. In order that the flow of voltage through any branch circuit 22 can be restricted for the functional purpose to appear presently, each said 30 branch circuit is provided with a high resistance 35 23 in series therewith.

Proceeding now with a description of the stop 50 of the upper manual, it will suffice to say that the contact elements 222 thereof are substantially 45 the same as the contact elements of the switches of the aforementioned playing keys, except that each contact element has a high resistance 25 in series at its output side, whereas and with respect to said playing key switches, the aforementioned high resistances 23 are at the input sides of said contact elements 21. When the stop is retired as shown in Figure 2 all contact elements 222 are open circuited. When the stop is drawn, the contact elements make close circuit 55 connection with their respective busbars 20, whereby voltages impressed thereon can be conducted to an amplitude grading resistor 24, the latter tapped in ten logarithmic steps corresponding 60 to 3 decibels each as indicated by corresponding numbers in Figure 2. Hence, when the stop is drawn and key C1 and/or C2 depressed, voltages from alternators which supply said key or keys will be conducted to said resistor and their relative intensities correctly graded. For example, 65 voltage at the sub-fundamental frequency of the note C1 will be conducted to tap 1. Voltage of the fundamental frequency of the said note is conducted to tap 10. In like manner, others of the voltages will be conducted to said resistor as shown and graded before they are delivered to an amplifying system to be described later.

If a partial is desired at full strength, the voltage corresponding to the frequency thereof connects with the common ground conductor, as 75

shown, the resistor 25 or 86, as the case may be, serving to limit the flow of voltage from the bus-bar from which said voltage is being delivered.

The stop 80 for the upper manual is the same in every particular as the stop 50 and has ten contact elements 85, each of which is individual to a particular bus-bar 20. The relationship between the contacts and coating bus-bars is the same as set forth in the description of the contact elements 222 of said stop 50. In series with each contact element 85 is a high resistance 86 and as shown in Figure 2, said elements are tapped to the resistor 24 for such gradation of the partials as is required for a predetermined tone quality.

It is assumed that stops 80, 90 and 100 shown in Figure 2 are coaxially related, each in coating relation to a cam 105. The cams are mounted to turn with a common shaft 106. The sets of switches 80, 90 and 100 constitute the different sets of crescendo stops and same are mounted in a case 107 as shown in Figure 4. Each switch is provided with a vertically movable arm 108 which projects through a vertical slot 109 in one wall of said case and is disposed beneath an associated cam 105. In order that the switches may be progressively actuated, the cams 105 are adjustably mounted on said shaft and adapted to be secured in set positions of angular adjustment by set screws 110. In this manner, the order in which the switches are close circuited can be accurately controlled. In Figure 4 I show a set of six multiple switches for the upper and lower manuals and a set of four multiple switches for the pedal keyboard. The cams for each of said multiple switches are set so that when the shaft is turned in one direction, the switches of the respective sets will be progressively actuated. The shaft may be operated by a foot pedal, not shown, and when the pedal is fully depressed, all of said switches will be close circuited. The speed at which the switches are open and close circuited may thereby be controlled for any desired musical results.

Assuming that four qualities are desired of the stops 80, five of the stops 90 and three of the stops 100, the partial mixtures for the various qualities may be in accordance with the following scheme:

connected to the terminals 230 and 240 of the resistors 24 and 224. As no claim is made for said system per se, it will be sufficient merely to mention that in order that the volume of sound elicited from the upper manual can be controlled independently of the lower manual and the pedal keyboard, use is made of potentiometers 250 and 260, the operation of each of which can be controlled from a separate expression pedal. In practice, the pedals will be closely related to each other so that they can be either singly or simultaneously controlled with one foot of the player, thus leaving the other foot free for operating the respective crescendo stops. The control pedal for the crescendo stops will be situated, preferably at the right hand side of the expression pedal for said lower manual and said pedal keyboard.

Connected to the output of the amplifying system is an electrical sound producer 210 of any well known construction.

From the foregoing description, it is appreciated that when the crescendo stops are open circuited, the stops 50, 60 and 70 can be selectively close circuited and as the stops 50 of the upper manual are connected in the amplifying system as shown, the volume of sound elicited from the upper manual can be controlled relative to that desired to be had when playing the lower manual and said pedal keyboard. When the crescendo stops 80, 90 and 100 are close circuited, the volume of sound for full organ and crescendo effects can be controlled as desired by simultaneously depressing the aforementioned expression pedals.

The impedance elements 19 are each variable from 0 to 2,000,000 ohms. The resistances 23 are each of the order of 2,000,000 ohms, the resistances 220 each of the order of 100,000 ohms and the resistances 25 and 86, each of the order of 500,000 ohms. The synthesizing resistors 24 and 224 are each of the order of 100,000 ohms.

By reason of the relative values of the aforementioned resistances, correct additive effects are had regardless of the number of playing keys simultaneously depressed and the number of stops close circuited at any instant. The term "stops" used herein shall include any of the speaking

50	Step	Quality	Range	Sub-fund	Fund	Sub-3rd	2nd	3rd	4th	5th	6th	7th	8th	50
Upper manual	1	String flute	8	0	4	0	2	3	3	2	2	2	1	
	2	Flutes	16	6	3	1	0	0	0	0	0	0	0	
	3	Flutes	4	0	0	0	6	0	4	0	1	0	0	
55	4	Trumpet	8	0	5	0	7	7	8	7	4	2	0	
Lower manual	1	String and flute	8	0	4	0	2	3	3	2	2	2	1	
	2	Flutes	16	8	3	2	0	0	0	0	0	0	0	
	3	Flutes	4	0	0	0	6	0	5	0	2	0	1	
	4	Open diapason	8	0	6	0	6	4	4	1	1	0	0	
Pedal	5	Tuba	8	0	7	0	7	7	8	5	3	0	0	
	1	Bourdon and string	16-8	6	1	1	2	2	2	1	1	1	0	
60	2	Tibia	16	8	4	3	0	0	0	0	0	0	0	
	3	Sub Tuba	16-8	5	7	6	7	6	6	5	3	0	0	60

The first crescendo stop 80 in the series of such stops for the upper manual is thus tapped to resistor 24 so that the relative intensities of the different partials will be as required for the production of a string and flute quality. The first crescendo stops 90 and 100 in the series of such stops for the lower manual and the pedal keyboard are each tapped to a resistor 224 in such manner that the partials controlled by the stop 80 will have their relative intensities graded for a string and flute quality, whereas, the stop 100, tapped as shown, will have its partials correctly graded for a bourdon and string quality.

In Figure 3, I show an amplifying system con-

55 stops for the upper and lower manuals and the pedal keyboard of the the instrument, and all of said crescendo stops for said manuals and said pedal keyboard.

In operation, any alternator when closed circuited in the electrical network herein shown, develops an alternating current drop across the impedance element 19 at the output side of said alternator, the value of the impedance being adjustable from zero to approximately the maximum output of said alternator.

When the key switches are close circuited, voltages flow through coating bus-bars 20 to ground through the resistors 220, which function to pro-

- duce an electrical relationship in the network between current and voltage such that the voltage drop across said resistors is always a function of the amount of current passing through them.
- 5 Consequently, the intensity of any particular frequency at the bus-bars is approximately a linear function of the number of resisted paths between an alternator and said bus-bars, thereby insuring that the volume of output shall be a function of
- 10 the number of notes simultaneously played and proportional to the number of speaking and crescendo stops close circuited at any instant, the resistors 25 and 86, serving to limit the transfer of energy from said bus-bars to an associated
- 15 amplitude grading resistor. As the value of each of said resistors 25 and 86 is definitely calculated as herein stated, it follows that a single stop when close circuited draws only a small amount of available energy from said bus-bars, whereby
- 20 when simultaneously playing a plurality of keys and close circuiting a plurality of stops, the number of resisted paths between said alternators and their coacting bus-bars proportionately increases in such manner that the total voltage
- 25 drop across an associated amplitude grading resistor likewise proportionately increases.

The term "speaking stop" employed herein shall mean any stop other than the crescendo stops or any musically useful coupling of two or

30 more stops.

What I claim as my invention is:

1. Mechanism for use in an electrical musical instrument employing selectors associated with different pitches and selector responsive means
- 35 for translating into sound alternating current potentials corresponding to said different pitches; said mechanism comprising a set of stops, each of which is actuatable to simultaneously render effective upon said translating means potentials
- 40 corresponding to harmonic partials of a tone of predetermined timbre, and an actuator common to all stops of said set of stops for actuating said stops to effect translation of potentials in accord-

ance with a predetermined successive order in which tones of different timbre are desired to be sounded.

2. Mechanism for use in an electrical musical instrument employing selectors associated with different pitches and selector responsive means for translating into sound alternating current potentials corresponding to said different pitches; said mechanism comprising a set of stops, each of which is actuatable to simultaneously render effective upon said translating means potentials corresponding to harmonic partials of a tone of predetermined timbre, and an actuator common to all stops of said set of stops for actuating said stops to effect translation and addition of potentials in accordance with a predetermined successive order in which tones of different timbre are desired to be sounded and including a foot pedal, the extent of depression of which determines the extent of addition of different timbres.

3. Mechanism for use in an electrical musical instrument employing electrical alternators for producing alternating current potentials corresponding to different pitches, an electrical transmitting network having an output circuit provided with an electro-acoustic translating device for translating said potentials into audible sounds, and means in said network by which the output energy thereof is proportional to the number of potentials at any frequency simultaneously transmitted through said network; said network comprising a set of stops connected in said network and each thereof actuatable to simultaneously render effective upon said translating device from different alternators potentials corresponding to harmonic partials of a tone of predetermined timbre, and an actuator common to all stops of said set of stops for actuating said stops to effect translation of potentials in accordance with a predetermined successive order in which tones of different timbre are desired to be sounded.

JAMES MANATT.
